CLAIM

(21) Appl. No.: **29/323,778**

The ornamental design for double ended microelectronic connector, as shown and described.

(22) Filed: **Aug. 29, 2008**

DESCRIPTION

(51) **LOC (9) Cl.** **13-03**

The double ended microelectronic connector is used for making an electrical and mechanical connection to mating ball terminals as shown with broken line in FIG. 7.

(52) **U.S. Cl.** **D13/133; D13/154**

FIG. 1 is a perspective view of a double ended microelectronic connector showing my new design;

(58) **Field of Classification Search** D13/133–136,

FIG. 2 is a front elevational view thereof, the rear elevational view being identical to the front elevational view;

D13/154, 184, 199; 439/168, 220, 226, 232,

FIG. 3 is a left side elevational view thereof;

439/280, 336, 419, 602; D26/24, 113; 313/318.01–318.05,

FIG. 4 is a right side elevational view thereof;

313/318.12; 362/260, 581

FIG. 5 is a bottom view showing a tubular base thereof;

See application file for complete search history.

FIG. 6 is a top plan view thereof; and,
